(57) **CLAIM**

The ornamental design for an optical connector plug as shown and described.

DESCRIPTION

FIG. 1 is a front, top and left-side perspective view of an optical connector plug showing my new design;

FIG. 2 is a front, bottom and left-side perspective view thereof;

FIG. 3 is a rear, bottom and right-side perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof;

FIG. 9 is a bottom plan view thereof;

FIG. 10 is an enlarged view of FIG. 6;

FIG. 11 is an enlarged view of FIG. 7;

FIG. 12 is an enlarged view of the area 12 indicated by the double dot-dash broken lines in FIG. 8; and,

FIG. 13 is an enlarged view of the area 13 indicated by the double dot-dash broken lines in FIG. 9.

The evenly spaced broken lines are provided to show portions of the optical connector plug that are not being claimed, and thus form no part of the claimed design. The double dot-dash broken lines shown in FIG. 8, FIG. 9, FIG. 12 and in FIG. 13 illustrate the boundaries of enlarged areas of the design. The “12” and “13” indicia and splined curve shown in FIG. 8 and in FIG. 9 identify the enlarged areas. The double dot-dash broken lines form no part of the claimed design.
